LIGHTNING ARRESTER

Clifford W. Petersen, Wauwatosa, Wis., assignor
to McGraw Electric Company, Milwaukee, Wis.,
a corporation of Delaware

Application November 3, 1951, Serial No. 254,707

11 Claims. (Cl. 313—243)

1

This invention relates to an improvement in lightning arresters, for the protection of electrical distribution systems and conductors, and in particular to an improvement in electrodes used in spark gaps.

It has been found that spark gaps using electrodes in a ladder-like formation between insulating spacers operate more effectively when a low impulse ratio can be achieved. A low impulse ratio makes it possible to have greater uniformity of spark-over between the electrodes, thus allowing the excess current to be more readily dissipated.

To obtain a low impulse ratio, some form of ionizing radiation must be present. This radiation is emitted from discharges existing between the electrodes and the insulating spacer accompanying the dielectric displacement current. The intensity of this radiation is proportional to the dielectric displacement current so that spark gaps with spacers of high dielectric constant material give lower impulse ratios.

It is an object of this invention to provide an improved condition for uniform spark-over.

Another object of this invention is to provide a means of holding the electrodes tightly against the insulating spacer.

It is also an object of this invention to provide an electrode for a lightning arrester in which expansion and contraction due to thermal differences between the various materials is taken care of to insure a firm contact between the electrode and the spacer.

And in particular it is an object of this invention to provide an electrode that contacts the insulating bushing in such a manner so that the dielectric field set up by the electrodes will create an area of radiation in the air spaces between the electrodes.

Other objects will appear from time to time in the course of the specification and claims.

I illustrate my invention more or less symbolically in the accompanying drawing, in which:

Fig. 1 is a standard spark gap shown partly in section with my improved electrode incorporated.

Fig. 2 is an enlarged view of my improved electrode illustrating the dielectric fields and the area of radiation.

Fig. 3 is an enlarged view of a variation of my improved electrode illustrating the dielectric fields and the area of radiation.

Like reference figures illustrate like parts throughout.

In Fig. 1, I show my improved electrode incorporated in a standard spark-gap consisting of a

2

housing 1 which is tubular and has a straight bore 2 throughout. This housing 1 is partially filled with a granular material 3 such as silicon carbide and is provided with a lower plate 4 and an upper plate 5 at opposite ends of the granular mass 3. The lower plate is sealed in place by means of a soft metal seal 6 bonding the stranded portions of a ground conductor 7 to the metal plate 4 and also conforming to the interior of the housing 1, and a rubber annular wedge-shaped gasket 8 spaced from the granular material. The lower portion of the arrester is completed by providing an asphalt seal 9 and a sulphur compound seal 10, although other sealing means may be used if desired.

The upper plate 5 has soft metal 11 molded in place above it. The upper end of the housing is closed by a spring copper cap 12 which has downwardly turned flanges 12a overhanging the upper edge of the housing. These flanges have a soft metal 13 poured into place and molded as shown, in interlocking relation with the housing or so as to hold the metal cap under tension and thereby transmit tension downwardly through the spark gap, hereinafter described, to the granular material.

The device may be covered by an insulating cap 14 with an asphalt cement 15 poured between the flanges 12a and the cap 14. A line conductor 16 is bonded in place to the metal cap 12 by the soft metal seal.

A round headed upper screw 17 fits within a recess in the cap 14 and passes through the upper end member or plate 18 of the spark gap and into the uppermost electrode at 19. This screw 17 locks the spark gap assembly together to make a unitary structure.

Within the housing 1 is a pair of insulating uprights 21 of some insulating material such as steatite. These uprights 21 form a spacing device for the electrode of the spark gap by means of machined openings 22 which provide the ladder-like supports for the electrodes 23.

These electrodes 23 consist of solid turned metal, either brass or some other suitable material. Referring to Fig. 2, the middle wider portion has tapered ends 24 and the two extremities 25 are machined to a smaller diameter to fit into the series of openings 22 in the insulating uprights 21.

The extremities 25 of the electrode are sufficiently smaller than the opening 22 in the uprights 21 so that a split eyelet 26 can be inserted around the extremities 25, and within the opening 22. This split eyelet is of such a size as to

make a firm contact between the extremities 25 of the electrode 23 and the uprights 21 and because of the split it has a spring action which insures this contact.

Where the metal and the insulation meet in sharp contact within the spacer and on its surface, a dielectric fringe effect is set up as shown at 27 in Fig. 2. This fringe effect causes a dielectric field 28 within the insulating uprights 21 between the contact points. The dielectric field sets up ionization and it is the radiation 29 of the ions extending across the air gaps between the electrodes that produces a steadyng effect on the spark-over. These lines of radiation tend to eliminate erratic spark-over.

In Fig. 3, I show a variant form of electrode to achieve a similar result. In this form the electrode 30 has an integral washer on one end and in the opposite end has a bore 31 through its midline section extending somewhat more than half way through the electrode. The electrode shank 32 is a separate piece with a washer 33 integral with it. It is inserted into the bore along with a spring 34. This spring action holds the washers 33 at both ends in firm contact against the insulating uprights 21 under shifting conditions or temperature changes which cause varying contraction and expansion with materials that having different coefficients of expansion.

Thus, it can be seen that by improving the construction of the electrode so as to insure a firm fit under any conditions of the electrode and the insulation, because of the tension means in the eyelet 26 of Fig. 2 or the spring means 34 of Fig. 3, the radiation means is intensified and uniform. With this great improvement in the area of radiation between the electrodes, the spark-over becomes uniform and a low impulse ratio can be had. When lightning strikes along the line, it is quickly and evenly dissipated through this improved lightning arrester.

I claim:

1. In a spark gap, a series of electrodes arranged in ladder-like construction between two upright insulating spacers, a member having uniform contact surface between the electrode and the insulating spacers to provide positive ionizing radiation within the gap.

2. In a spark gap, a series of electrodes arranged in ladder-like construction between two upright insulating spacers, a tension eyelet inserted between the electrode and the insulating spacer to create a firm contact between them, the points of contact between the electrode's tension eyelet and insulation, setting up a dielectric field between the electrodes, said dielectric field causing ionization which radiates to the air spaces between the electrodes.

3. In a spark gap, a series of electrodes arranged in ladder-like construction between two upright insulating spacers, a split eyelet inserted between the electrode and the insulating spacer to create a firm contact between them, the points of contact between the electrode's eyelet and insulation setting up a dielectric field between the electrodes, said dielectric field causing ionization which radiates to the air spaces between the electrodes, said lines of ionized radiation causing a uniform spark over between the electrodes.

4. In a spark gap, a series of electrodes arranged in ladder-like construction between two upright insulating spacers, a flanged tension eyelet inserted between the electrode and the in-

5. insulating spacer to create a firm contact between them, the points of contact between the electrode's said tension eyelet and insulation, setting up a dielectric field between the electrodes, said dielectric field causing ionization which radiates to the air spaces between the electrodes, said lines of ionized radiation allowing a low impulse ratio in the spark gap.

6. In a spark gap, a series of electrodes spaced vertically, the ends of the electrodes inserted in openings in an insulating spacer, a split metal eyelet inserted between the electrode ends and the openings in the insulating spacer and making a firm contact between them.

7. In a spark gap, a series of electrodes spaced vertically, the ends of the electrodes inserted in openings in insulating spacers, a split metal eyelet inserted between the electrode ends and the openings in the insulating spacer making a firm contact between them, the contact points between the eyelet and the insulation setting up a dielectric field between contact points of adjacent electrodes, said dielectric field emitting ionized radiation into the air spaces between the electrodes.

8. In a spark gap, a ladder-like series of electrodes, with machined ends that fit into openings in insulating spacers, a combination split eyelet washer and sleeve fitted under tension between the ends of the electrode and the opening in said insulating spacer.

9. In a spark gap, a ladder-like series of electrodes, with machined ends that fit into openings in insulating spacers, a combination split eyelet washer and sleeve fitted under tension between the ends of the electrode and the opening in said insulating spacers, the said tension causing a firm fit between electrode, washer, and insulating spacer.

10. In a spark gap, a ladder-like series of electrodes, with machined ends that fit into openings in insulating spacers, a combination split eyelet washer and sleeve fitted under tension between the ends of the electrode and the opening in said insulating spacers, the said tension causing a firm fit between electrode, washer, and insulating spacers, when thermal changes cause uneven expansion and contraction of the various parts.

11. In a spark gap, a ladder-like series of electrodes, the ends of said electrodes inserted in openings in two upright insulating spacers, said electrodes consisting of one end of smaller diameter than the middle portion and having an integral washer, contacting the inner side of one insulating spacer, a bore extending inwardly through the electrode from its other side, said bore holding a spring and a piston-like member with integral washer, said piston-like member contacting the spring on its inner end and the insulating spacer on its outer end, the spring means thrusting outwardly the two ends with their integral washers making a firm contact between washer and insulating spacer.
